UNITED STATES PATENT OFFICE

CALVIN K. KAZANJIAN, OF NAUGATUCK, CONNECTICUT, ASSIGNOR TO J. N. COLLINS COMPANY, OF FRANKFORD, PENNSYLVANIA, A CORPORATION OF DELAWARE

DESIGN FOR A CANDY DISPLAY CONTAINER

Application filed November 9, 1931. Serial No. 41,661. Term of patent 14 years.

To all whom it may concern:

Be it known that I, CALVIN K. KAZANJIAN, a citizen of the United States, residing at Naugatuck, in the county of New Haven and State of Connecticut, have invented a new, original, and ornamental Design for a Candy Display Container, of which the following is a specification, reference being had to the accompanying drawing, forming part thereof.

The figure is a perspective view of a candy display container showing my design.

I claim:

The ornamental design for a candy display container, as shown.

Naugatuck, New Haven County, Connecticut, October 29th, 1931.

CALVIN K. KAZANJIAN.
